UNITED STATES PATENT OFFICE

166,918

SEAT COVER

George Joseph Kramer, Bristol, Conn.

Application February 12, 1952, Serial No. 18,485

Term of patent 14 years

(Cl. D90—16)

To all whom it may concern:

Be it known that I, George J. Kramer, a citizen of the United States, residing at Bristol, Connecticut, have invented a new, original, and ornamental Design for a Seat Cover, of which the following is a specification, reference being had to the accompanying drawings, forming part thereof.

Figure 1 is a top plan view of a seat cover showing my new design,

Figure 2 is a rear elevational view thereof, and Figure 3 is a side elevational view thereof.

I claim:

The ornamental design for a seat cover, substantially as shown.

GEORGE JOSEPH KRAMER.
